HINGED HASP FASTENING

Charles William Cheney, Soho, Birmingham,
EnglandApplication January 2, 1936, Serial No. 57,215
In Great Britain April 17, 1935

5 Claims. (Cl. 292—281)

The invention relates to a hinged hasp fastening of the kind used on an attaché or suit case or the like.

Such a fastening comprises two main parts, one 5 an attachment plate, and the other a hasp hinged to the attachment plate by a hinging pin.

The invention provides in such a fastening a combination of parts, the primary one of which is a hasp formed from sheet metal and comprising front and back plates integrally joined up at that end of the hasp where the staple or loop is applied, the front plate having opposite hinging lugs and a crossing hood rigidly connecting said lugs.

The combination of parts will be hereinafter clearly set out in the claims and described with reference to the accompanying drawing, and same results in a very strong, efficient and cheap hasp fastening.

Fig. 1 is a front elevation.

Fig. 2 is a longitudinal section of Fig. 1.

Fig. 3 is a back elevation of Figs. 1 and 2.

Fig. 4 is a cross-section of Fig. 3 on the dotted lines A—B.

Fig. 5 is a section showing the hasp only with its front and back plates partly closed to each other.

Fig. 6 is a back view of a hasp modified in detail.

Fig. 7 is a longitudinal section of Fig. 6.

Fig. 8 shows a modification of Fig. 4.

With reference to Figs. 1—5, the fastening comprises two main parts, an attachment plate 1 and a hasp 2, hinged together by a hinging pin 3.

Said attachment plate, preferably formed from sheet metal, has an opposite pair of lugs 4 and 5 formed with holes for the hinging pin, and a hood 6 rigidly connecting said lugs, and a boundary flange 7 joining up with the lugs 4 and 5, to thereby provide an inexpensive and strong form of attachment plate member.

The hasp 2, formed from sheet metal, comprises front plate 8 and back plate 9 integrally joined up at 10, near to where the staple or loop 11 is applied to the back plate, by doubling the blank upon itself at the part 10, the staple 11 being rigidly riveted to the back plate 9.

Said front plate 8 has an opposite pair of hinging lugs 12, 13 and a hood 14 rigidly connecting said lugs, and also a boundary flange 15 joining with the lugs except at that part 10 where the doubling of the blank takes place, said flange being at this part cut away. The lugs 12, 13 each

have a hole in them to receive the hinging pin 3.

The back plate 9 is also provided with an opposite pair of lugs 16 and 17 having a hole in each of them to receive the hinging pin, and has a boundary flange 18 joining with the lugs 16 and 17 and extending to near the point 10 where the front and back plates integrally join up.

The flange 18 of the back plate is made to closely fit within the flange 15 of the front plate, as clearly shown in Figs. 3 and 4, and the pair of lugs 16, 17 of the back plate to fit between the lugs 12 and 13 of the front plate, as clearly shown in Figs. 1, 2 and 3, the one plate transversely supporting the other.

When the closed hasp 2 is applied to the attachment plate 1 the pair of lugs 16, 17 engages between the pair of lugs 4 and 5, and the hood 14 engages within the hood 6, in which position of parts the hinging pin passes through the holes of all the three pairs of lugs and is riveted at its ends as clearly shown in Figs. 1 and 3, but previously to riveting a coiled spring 19 may be applied over the hinging pin to operate in torsion between the attachment plate and the hasp.

In the modification Figs. 6 and 7 the back plate 9 is without opposite lugs or boundary flange, but fits closely within the boundary flange 15, and is held therein by inwardly turned ears 20 and 21 upon the boundary flange 15. Otherwise, this modification is the same as the construction described with reference to Figs. 1—5.

In the modification Fig. 8 the back plate 9 is without a boundary flange but fits closely with in the boundary flange 15 of the back plate by engagement of the hinging pin 3.

The attachment plate part 1 is preferably made from sheet metal, but it may be a cast metal part.

Having now described my invention, what I claim and desire to secure by Letters Patent is:—

1. In a hinged hasp fastening, the combination of an attachment plate having an opposite pair of hinging lugs; a hasp formed from sheet metal and comprising front and back plates integrally joined up at that end of the hasp where the staple is applied, said front plate having an opposite pair of hinging lugs and a hood rigidly connecting said lugs, the hasp lugs to engage between the lugs of the attachment plate; means for fixing the loose end of the back plate; and a hinging pin passing through the engaging pairs of lugs to hinge said attachment plate to the hasp, substantially as described.

2. In a hinged hasp fastening, the combination of an attachment plate formed from sheet metal and having an opposite pair of hinging lugs and a hood rigidly connecting said lugs, and also a boundary flange joining with said lugs; a hasp formed from sheet metal and comprising front and back plates integrally joined where the staple is applied, said front plate having an opposite pair of hinging lugs to engage between the lugs of the attachment plate and a hood rigidly connecting said lugs, and also a boundary flange joining with the lugs, the back plate fitting within the flanges of the front plate; means for fixing the loose end of the back plate; and a hinging pin passing through the engaging pairs of lugs, substantially as described.
3. In a hinged hasp fastening, the combination of an attachment plate formed from sheet metal and having an opposite pair of hinging lugs and a crossing hood rigidly connecting said lugs and also a boundary flange joining with said lugs; a hasp formed from sheet metal and comprising front and back plates integrally joined where the staple is applied, said front plate having an opposite pair of hinging lugs to engage between the lugs of the attachment plate, and a hood rigidly connecting said lugs, and also a boundary flange joining with the lugs, the back plate having a boundary flange to fit within the flanges of the front plate, and an opposite pair of lugs joining with these flanges at the loose end of the back plate; and a hinging pin passing through all the pairs of lugs.

4. In a hinged hasp fastening, the combination of an attachment plate having an opposite pair of hinging lugs; a hasp formed from sheet metal and comprising front and back plates integrally joined where the staple is applied, said front plate having a pair of opposite hinging lugs, a hood rigidly connecting the lugs, and a boundary flange connecting with the lugs; means for fixing the loose end of the back plate; a hinging pin passing through and engaging the 10 pairs of lugs, and a spring encircling the hinging pin and operating torsionally between the attachment plate and the hasp.

5. In a hinged hasp fastening, the combination of an attachment plate formed from sheet metal and having an opposite pair of hinging lugs and a hood rigidly connecting said lugs, and also a boundary flange joining with said lugs; a hasp formed from sheet metal and comprising front and back plates integrally joined where the 15 staple is applied, said front plate having an opposite pair of hinging lugs to engage between the lugs of the attachment plate, and a hood rigidly connecting said lugs, and also a boundary flange joining with the lugs, the back plate fitting within the flanges of the front plate; means for fixing the loose end of the back plate; a hinging pin passing through the engaging pairs 20 of lugs; and a spring encircling the hinging pin and operating torsionally between the attachment plate and the hasp.

CHARLES WILLIAM CHENEY.
